ENCLOSED ELECTRIC SWITCH

Carl W. Sundberg, Birmingham, Mich., assignor to Square
D Company, Detroit, Mich., a corporation of Michigan

Application April 20, 1953, Serial No. 24,593

Term of patent 14 years

(Cl. D26—13)

To all whom it may concern:

Be it known that I, Carl W. Sundberg, a citizen of the United States and a resident of Birmingham, in the county of Oakland and State of Michigan, have invented a new, original, and ornamental Design for an Enclosed Electric Switch, of which the following is a specification, reference being had to the accompanying drawing, forming a part hereof.

Figure 1 is a front elevational view of an enclosed electric switch showing my new design.

Figure 2 is a top plan view thereof.

Figure 3 is an elevational view looking toward the left of Figure 1.

Figure 4 is an elevational view looking toward the right of Figure 1.

Figure 5 is a bottom plan view thereof.
The dominant features of my design reside in those portions shown in full lines.

I claim:

The ornamental design for enclosed electric switch, substantially as shown and described.
